UNITED STATES PATENT OFFICE.

HENRY W. FISHER AND NORMAN C. DAVIS, OF PERTH AMBOY, NEW JERSEY,
ASSIGNORS TO STANDARD UNDERGROUND CABLE COMPANY, OF PITTSBURGH, PENNSYLVANIA, A CORPORATION OF PENNSYLVANIA.

CABLE-BUILDING MACHINE.

Application filed May 24, 1922. Serial No. 563,446.

To all whom it may concern:

Be it known that we, HENRY W. FISHER and NORMAN C. DAVIS, residing at Perth Amboy, in the county of Middlesex and State of New Jersey, both citizens of the United States, have invented or discovered certain new and useful Improvements in Cable-Building Machines, of which improvements the following is a specification.

10 It has heretofore been proposed, in the building of electric cables (see U. S. Letters Patent No. 1,009,732, granted November 28, 1911, to the Standard Underground Cable Company, on the application of Henry W. 15 Fisher, one of the present applicants), to apply strip-formed insulation (paper, for instance) to a conductor, by causing the conductor, while advancing in continuous length upon a right-line course, to rotate as it advances, and in so doing to wrap itself within the tape or tapes fed from adjacent stationary reels. This proposal, being carried out, has manifest advantages over the usual procedure, in which the advancing 20 conductor does not rotate, but the reels which carry the strips travel in planetary orbits around the line of conductor advance. Our present invention consists in improvements upon the disclosures of the Fisher 25 patent mentioned above; these greatly increase the commercial value of the original disclosure. The features of our present improvements may be enumerated and characterized briefly:

30 First: The number of strips or tapes which are applied to a conductor varies; it may often be very large—fifty say, or even two or three hundred. The mechanism required to drive so great a number of reels 35 in planetary motion around a single line of conductor travel must manifestly be very great, and it is manifest that the idea of imparting rotary movement to the conductor while the tape reels remain stationary is 40 one which, being realized, has manifest advantages. That idea is, in the practice of our invention, realized, and, furthermore, our improvements make possible the application of successive tapes at minimum intervals, in the closest possible sequence; and 45 from this it follows that the length of conductor extending in straight-away course and exposed for application of the tapes 50 may be reduced to a minimum, with saving

of floor space and simplification of conductor-moving mechanism.

Second: We provide torsion-resisting devices. It is manifest that a length of cable supported at its ends and rotated by force applied at the ends, and in its rotation drawing a tape from a source of tape supply and wrapping the tape about itself, is necessarily subjected to a torsion strain: some resistance has to be overcome by the turning conductor in drawing the tape to itself. As presently will appear we find it desirable for other reasons to make this resistance a substantial one in amount; if there be many tapes (the direction of winding being of necessity uniform) the aggregate resistance may be very great. Our tension-resisting devices may be one or many, stationed at suitable point or points along the exposed length of conductor, subdividing the distance into shorter spaces, in which the torsion strain is broken and subdivided, and made operative upon shorter lengths of conductor. Thus the torsion strains are rendered ineffective to disturb practical, successful operation.

Third: We provide tension devices through which the tapes pass after leaving their reels and before being applied to the conductor. The tape reels are themselves left free to turn with a minimum degree of restraint, and, compared with the resistance of the reels, the resistance afforded by these tension devices is great. The consequent advantages are that, whether drawn from a full or from an empty reel, the constantly speeded strip advances to and is laid down upon the conductor under a practically uniformly maintained tension; that the actual value of this uniform tension may be adjusted to other conditions of cable building; that in such a tension device all distorting strains may be counteracted, and the tape may be laid down upon the conductor free of all tendencies to buckle or wrinkle; and that the tape reels may be located where one will, near or far, and in such locations as to be free of access and non-interfering one with another. Another advantage of the use of the tension device and of remote placement of the reel, is that, when the reel is emptied, it may be replaced by a full one and the ends of the tapes may be joined, all without disturbance of the con-

tinuous operation of the whole. And still another advantage is found in a provision which we shall describe, which makes for easier and more certain inspection of the 5 tapes as they advance to the conductor.

In the accompanying drawings Fig. I is a view in vertical and longitudinal section of apparatus for wrapping strips or tapes upon conductors, and in which certain of the 10 improvements which constitute our present invention are shown to be incorporated, and in the assembly and use of which all of our improvements may, as presently will appear, be incorporated. Fig. II is a view in 15 transverse vertical section through an advancing conductor and showing in elevation and in cooperation with it the elements of a certain torsion-resisting device. The plane of section of Fig. II is indicated in Fig. I 20 by the dotted line II-II. Fig. III is a view in perspective, showing in diagrammatic manner the tension device. Fig. IV is a diagrammatic view in side elevation of the assembled apparatus, viewed in a direction longitudinal of the conductor, the 25 conductor itself being shown in cross section. Fig. V is a view in vertical section through shaft 8 and showing in elevation a certain sprocket drive mechanism for rotating certain parts synchronously with the 30 cable.

Referring first to Fig. I of the drawings, a storing reel for the still unwrapped conductor is indicated at 1, a take-off drum for 35 the wrapped conductor is indicated at 2, and a receiving reel for the wrapped conductor at 3. The conductor under treatment (it is gradually enveloped) is indicated at C; the direction of its right-line advance is from 40 right to left, as is indicated by the arrow d.

The two reels and the take-off drum mentioned are mounted in alignment, as shown, their axes extend transversely of and intersect the midline of conductor advance, a-b. 45 The reels have two motions: they rotate, each on its axis, and they rotate also, and in synchronism, upon the line a-b as an axis.

The means for synchronously rotating the 50 two reels 1, and 3 and the take-off drum 2, upon the line a-b as an axis of turning, are shown. Reel 1 is journaled in a frame 4, and frame 4 in turn is journaled in standards 5; take-off drum 2 and reel 3 are both 55 journaled in one frame 6, and frame 6 in turn is journaled in standards 7. Frames 4 and 6 are rotated from a driven shaft 8, through pinions 9, 10, 11, 12.

Ordinarily reel 1 will be mounted for idle 60 turning on its axis in response to tension upon the conductor, tending to unwind it. Drum 2 and reel 3 will be positively driven each rotating upon its own axis. Provision will be made, in well-known manner that 65 the length of conductor (now wrapped) ex-

tending from drum 2 to reel 3 shall always be taut, regardless of the depth to which the conductor may be wrapped on reel 3. For example, reel 3 may be driven through a variable speed friction drive. 70

The frames 4 and 6 are provided with guides 13 and 14, through which the conductor advances from reel 1 to drum 2, and these guides are the primary means for maintaining the intervening length of conductor in straight-away course, and in proper position to receive the enveloping strips of insulation. 75

Between the frames 4 and 6 and arranged to engage the length of material which extends between guides 13 and 14, is arranged one, or any desired number of torsion resisting devices. These are employed in such number and are so spaced along the length of material which extends between guides 13 80 and 14, as to subdivide the extent of the material into a plurality of shorter reaches of suitable length. We show one torsion-resisting device, and one reach of the length of conductor defined by it—the reach between it and guide 14. This illustration will suffice; duplication to any desired degree will be obvious. 85

The torsion-resisting device consists essentially of a member which, not interfering to 90 a prohibitive degree with the advance of the conductor along the line a-b, engages the surface of the conductor, more or less enveloped, and by engagement resists such tendency as may manifest itself in the conductor, to depart torsionally from rotation at uniform rate from end to end, in accord with the rotation of frames 4 and 6. 95

The specific form of such means may vary. The form we preferably employ is particularly illustrated in Figs. I and II of the drawings. It consists of a ring 15, mounted for rotation in a suitable standard 18, arranged in axial alignment upon the line a-b, and adapted to be rotated in synchronism with frames 4 and 6. The driving means may conveniently consist of a sprocket drive indicated at 17 from a sprocket wheel mounted on shaft 8. The sprocket drive effects rotation of the gear 115 wheel 23 which meshes with a gear wheel integral with ring 15. 110

The ring 15 internally engages the exterior surface of the conductor passing through and is minutely shaped to that end. Such 120 conductor engaging surfaces may conveniently take the form of anti-friction rollers 16 (so imposing in minimum degree added resistance to the longitudinal advance of the conductor upon the line a-b). The rollers 125 16 are idly journaled in the body of ring 15, and their cooperating surfaces define a roll pass corresponding in shape and size to the advancing conductor. In the case shown the conductor is sector-shaped, but even 130

were it circular it will be understood that correspondingly shaped rollers would by their frictional contact with the surface of the conductor be effective to resist torsion strains to which the conductor might otherwise respond. The closeness with which the tension device engages the advancing conductor is of course a matter which may be very accurately predetermined.

10 Strips of paper or of other material adapted to be similarly applied are indicated at S in course of multiple application spirally and successively to the conductor C advancing in the direction indicated by arrow d. The number of such strips so applied to the conductor in each of the intervals defined by the torsion-resisting devices may be such as desired. In the interval immediately to the left of guide 13 20 we show three such strips in course of application; in the interval to the left of tension-resisting device 15, and between it and guide 14, we show four strips in course of application.

25 Whatever be the actual value of the resistance to be overcome in drawing strips S forward and wrapping them upon the conductor C, it must, under practical conditions, be appreciable. And conductor C rotated with frames 4 and 6 is itself the mechanical means through which traction strain is exerted on the strips. The cumulative effect of a large number of such small strains, tending to distort the conductor torsionally, may be very great, and the aim and end of the torsion-resisting means now described are apparent: the aggregate sum is subdivided into a plurality of smaller sums, and manifestly the particular arrangement will be such that no single smaller sum is of sufficient magnitude to forbid practical operation and successful production for purposes intended.

30 Fig. III shows a suitable tension device for the strip S. Ordinarily there will be a separate tension device for each strip, though as the drawing suggests a plurality of tension devices may have structural parts in common. The tension device is arranged 40 at a convenient intermediate point, between the reel 19 from which the strip is drawn and the conductor C upon which it is laid down.

35 The tension device may conveniently consist of two plates 20 and 21 arranged face to face and bolted together at opposite sides of the pass between, by such spring-backed means of bolting as the drawings show, and which, being a well known arrangement, 50 does not require detailed description. The characteristic features are that the opposite plates are held under spring pressure toward one another and in close frictional engagement upon opposite sides of the passing strip; and, further, that the distribution of

the pressure may be varied and equalized across the strip by proper adjustment of the opposite bolts. The friction exerted in this tension device will so far exceed the resistance which the reel 19 offers to unwinding strain that that resistance (varying as of necessity it does, if only because of increased speed as the spool becomes emptied) is blanketed and is practically ineffective to disturb the substantially constant condition of tension set up by the tension device.

55 When the principle and purpose of this tension device are clearly understood the value of the torsion-resisting means already described become the more apparent.

Fig. III indicates that plate 20 may be so extended as to form with a succession of plates 21 a plurality of tension devices.

60 The tension devices are placed in such position relative to the length of conductor advancing between frames 4 and 6 as may be found convenient; and, such tension devices being provided, manifestly reels 19 may be placed at such near or remote points as may be convenient. Reels 19 being remote from the tension devices, it is evident that facility exists for replacing an empty reel with a full one and uniting the end of a new strip to the used-up strip before that end reaches and passes through the tension device, and that without intermission of the continuous progress of the operation as a whole. It will be apparent that such a tension device as is described in the co-pending application of Norman C. Davis, one of the 100 present applicants, filed July 7, 1922, Serial No. 573,424, may be employed, even though the device be not remote from the reel.

65 Turning to Fig. IV a convenient arrangement will be seen, diagrammatically indicated. A tension device, indicated by the numeral 20, is shown, arranged adjacent the turning and advancing conductor C; it will be understood that a plurality of such tension devices may stand side by side along the length of conductor C. A plurality of tapes S is shown, advancing from reels 19, and these tapes will be understood to be advancing through such a plurality of tension devices, and in the course of being wrapped about the conductor C. A bar 22 is provided suitably arranged, to the end that all of the tapes are caused to pass over it, side by side, on their way from the reels to the conductor. Such a bar is of value, in that it brings into view under uniform conditions of vision the plurality of tapes, and, 110 bar 22, being suitably placed, means for inspection and ready detection of faults are 115 at hand. It is advantageous that this bar be arranged as shown, to rearward of and at some substantial distance from the tension devices, to the end that flaws may be 120 cut out and the cut ends of the strip united 125 130

again, without interruption of the wrapping operation. The emptying of a reel is of course immediately apparent in an assembly such as Fig. IV shows.

5 Some of these advantages may still be realized, even though no separate bar 22 be employed, the plate 20 of the tension devices serving in some degree the same ends. If it were desired such a bar might manifestly be placed in intermediate position, between tension devices and conductor.

We claim as our invention:

1. In a taping machine the combination of means for causing the article under treatment to advance on straight away course rotating as it advances, means for placing under tension a tape secured to the article under treatment and drawn forward by the article as it advances, and means adapted to engage the surface of the advancing article and by such engagement to oppose torsional stress upon the article, substantially as described.

2. In a conductor-insulating machine, the combination of means for causing a conductor to advance upon a straight-away course, rotating as it advances, torsion-resisting means adapted to engage a conductor so advancing, and means for holding under tension a plurality of strips of insulating material fed to such an advancing conductor on either side of said torsion-resisting means, substantially as described.

3. In a taping machine the combination of means for causing the article under treatment to advance on straight-away course, rotating as it advances, means adapted to engage the surface of an article so advancing, rotatable, in unison with the article, and adapted while offering relatively little resistance to the straight-away advance of the article, offering relatively great resistance to torsional deformation thereof, and means for holding under tension a length of tape secured to the advancing article, substantially as described.

4. In a taping machine the combination of means for causing the article under treatment to advance on straight away course, rotating as it advances, torsion-preventing means adapted to engage said article while rotating in unison with it, a plurality of tape reels, and a bar adapted to engage the tapes advancing from said reels to the article, substantially as described. 50

5. In a taping machine the combination of means for causing the article under treatment to advance on straight-away course, rotating as it advances, torsion preventing means adapted to engage the advancing article, a tape reel, and a tension device adapted to engage a web of tape advancing from said reel to the article under treatment. 55

6. In a taping machine the combination of means for causing the article under treatment to advance on straight-away course, rotating as it advances, torsion-preventing means adapted to engage such article at an intermediate point in such straight-away course, a plurality of tension devices adapted to engage tapes fed to an article under treatment, said tension devices being individually adjustable in their tension-giving effect, substantially as described. 60

7. In a taping machine the combination of means for causing an article under treatment to advance on straight-away course together with a tape reel, one of said parts being rotatable relatively to the other on the line of cable advance as an axis of rotation, and means engaging the article under treatment at an intermediate point in the length of its straight-away course and by such engagement resisting distortion thereof. 75

In testimony whereof we have hereunto set our hands.

HENRY W. FISHER.
NORMAN C. DAVIS.
